(57) **CLAIM**

The ornamental design for a precious stone cut, as shown and described in the accompanying figures.

DESCRIPTION

FIG. 1 is a side view of an embodiment of a precious stone illustrating an embodiment of my new design for a precious stone cut;

FIG. 2 is another side view showing the precious stone rotated 45 degrees about a center axis from the position illustrated in FIG. 1;

FIG. 3 is a top plan view of the precious stone illustrated in FIG. 1;

FIG. 4 is a bottom view of the precious stone illustrated in FIG. 1;

FIG. 5 is a side view of an embodiment of a transparent precious stone illustrating an embodiment of my new design for a precious stone cut;

FIG. 6 is another side view showing the transparent precious stone rotated 45 degrees about a center axis from the position illustrated in FIG. 5;

FIG. 7 is a top plan view of the transparent precious stone illustrated in FIG. 5; and,

FIG. 8 is a bottom view of the transparent precious stone illustrated in FIG. 5.

All portions shown in broken lines are environmental and illustrative only and form no part of the claimed design.
